SPRING COIL HANDLING APPARATUS

Frank N. Schindler, Chicago, Ill., assignor to A. Brandwein & Co., Chicago, Ill., a corporation of Illinois

Application January 21, 1937, Serial No. 121,605

12 Claims. (Cl. 198—131)

This invention relates to conveying devices and particularly to novel means for conveying spring coils through treating enclosures such, for example, as ovens or the like for heating the coils during the process of tempering.

One object of the invention is to provide a novel conveyor construction whereby the spring coils may be carried through the oven in spaced or separated relation with respect to each other.

Another object of the present invention is to provide novel means for conveying spring coils through a tempering oven separately and in spaced relation and in a manner to subject all the coils to substantially the same heat treatment.

Another object of the invention is to provide a novel feeding or loading arrangement for delivering spring coils to the conveyor in a manner to be engaged thereby adjacent one end portion of the coils and for automatically removing the coils one at a time from the feeding means.

Another object of the invention is to provide novel means operatively related to the conveyor for retaining the spring coils in desired position whereby the coils are subjected to substantially uniform heat treatment during their passage through the oven, thereby producing a substantially uniform product.

A further object of the invention is to provide novel means for disengaging the spring coils from the conveyor after passing through the oven and directing them away from the conveyor.

A still further object of the invention is to improve devices of the character described in sundry details hereinafter referred to and particularly pointed out in the appended claims.

One embodiment of the present invention is shown for illustrative purposes in the accompanying drawings, in which:

Fig. 1 is a longitudinal sectional elevational view of a tempering oven illustrating the application of my improved conveying means thereto and illustrating also the application of improved feeding and discharge means in relation to said conveying means;

Fig. 2 is a plan sectional view of the structure illustrated in Fig. 1, and taken substantially as indicated by the line 2—2 thereof;

Fig. 3 is an enlarged elevational view illustrating a portion of the tempering oven in section and showing the feeding and conveying means as viewed on the line 3—3 of Fig. 1;

Fig. 4 is an enlarged fragmentary elevational view of a portion of the feeding means in relation to my improved conveyor, showing a portion 55 of the conveyor in changed position as indicated

by dotted lines, and illustrating the manner of removing the spring coils from the feeding or loading means;

Fig. 5 is an enlarged sectional elevational view of a portion of the discharge means taken substantially as indicated by the line 5—5 of Fig. 3;

Fig. 6 is an inside elevational view of a portion of the structure illustrated in Fig. 5, and taken substantially as indicated by the line 6—6 thereof; and

Fig. 7 is an enlarged transverse sectional elevational view taken substantially as indicated by the line 7—7 of Fig. 1.

The present invention is particularly well adapted for use in the treatment of spring coils such, for example, as coils for mattress construction, beds or other articles of furniture, and is shown in the present instance as related to a tempering oven indicated, as a whole, by the numeral 11, having heating units therein shown, 20 in the present instance, as gas burners 11a, and provided with an inlet opening and a discharge opening 12 and 13, respectively.

The conveyor is shown in the present instance as of a flexible link belt or chain type indicated, 25 as a whole, by the numeral 14 and suitably trained over sprocket wheels 15, 16, 17, 18, 19 and 21 by which the various runs of the conveyor are directed through the oven 11, and adjacent suitable feeding and discharge means indicated, as a whole 30 and respectively, by the numerals 22 and 23, the sprocket 15 being shown in the present instance, as mounted on a drive shaft 24 having a sprocket 25 outside the oven and adapted to be connected by means of a chain 26 or other suitable driving 35 means with a suitable source of power as, for example, an electric motor, engine or the like, not shown.

Suitably mounted at opposite sides of the conveyor 14 and extending substantially parallel 40 thereto through the oven 11 and between the feeding means 22 and the discharge means 23 are a plurality of pairs of guide rails or bars 27 and 28 having their adjacent edge portions spaced apart to provide an elongated slot or passage 29 45 at opposite sides of the conveyor 14 and extending substantially parallel thereto.

Mounted on the conveyor 14 and extending laterally therefrom and alternately at opposite sides thereof are a plurality of spring coil pick-up 50 and supporting pins 31 adapted to project through the slots 29 between the respective pairs of guide bars 27 and 28 at opposite sides of the conveyor, the pins 31 being provided at their outer ends 55

with heads 32 spaced from the outer sides of said guide bars.

The supporting pins 31 are shown in Figs. 4 and 6 as formed, preferably, by extensions of 5 certain of the pivot pins or bolts employed for connecting together a plurality of links 33 forming the conveyor 14.

For feeding the spring coils indicated by the character "S" to the conveyor 14 in a manner to 10 be picked up by the pins 31, the feeding or loading means 22 are positioned outside the oven 11 adjacent the inlet opening 12 and shown, in Fig. 3, as located at opposite sides of the conveyor in 15 a manner to feed the coils "S" thereto from both sides of the conveyor. The feeding means 22 are shown, in the present instance, as comprising feeder belts 34 trained over pulleys 35 and having inwardly sloping trough-like chutes 36 extending between the pulleys 35 and the conveyor 14 in a manner to direct one of the ends of 20 the spring coils "S" against the outer side portions of guide bars 27 and 28 positioned at opposite sides of the conveyor, the chutes 36 being provided with open portions adjacent their inner ends to permit the passage therethrough of the pins 31 in a manner to engage the end portion of 25 the coils adjacent the guide bars for removing them successively or one at a time from the chutes and carrying them through the inlet opening 12 and into the oven 11. The spring coils, after 30 leaving the chute 36, will be supported in substantially horizontal position by resting against the guide bars 27 and 28 and carried around the sprockets 17, 16 and 15, and through the oven in 35 such position and in spaced relation with respect to each other. From the oven 11 the coils "S" are conveyed through the outlet opening 13 to a pair of discharge chutes 23 positioned outside the oven 11 adjacent the outlet opening 13, the discharge chutes comprising oppositely disposed inclined side portions 37 forming a trough-like 40 chute sloping away from the conveyor. The inner or adjacent ends of the discharge chutes 23 are provided with oppositely disposed inclined stop plates 38 secured to the adjacent guide bars 45 27 and 28 at opposite sides of the slots 29 and cooperable with the guide bars to form a notch 39 on the upper side of the plates 38 adapted to be engaged by the inner end portion of the spring coil "S" in its downward movement from the oven and arrest the movement of the coil while 50 the supporting pin 31 continues its downward movement with the travel of the conveyor 14 until the pin 31 is completely disengaged from the coil "S", at which time the projecting portion of 55 the coil will drop by gravity into the chute 23 and be conducted therethrough away from the conveyor.

While, in the present instance, only one conveyor is shown in relation to the oven 11, it will 60 be understood that as many such conveyors may be operated within and through an oven as may be practicable.

The operation of the present invention is substantially as follows:

A plurality of spring coils "S" are fed to the 65 loading chutes 36 by the belts 34 and directed by the chutes against the guide bars 27 and 28 on the respective sides of the conveyor 14 in a manner to be picked up one at a time and in 70 spaced relation with respect to each other by means of the supporting pins 31 on opposite sides of the conveyor and carried upwardly through the inlet opening 12 into the oven 11 75 and longitudinally thereof in one direction,

around the sprocket 16 and longitudinally of the oven in the opposite direction, and thence downwardly and out of the oven 11 through the outlet opening 13 to the discharge chutes 23 where the movement of the spring coils is arrested by 5 the stop plates 38 until the supporting pin 31 has cleared the coil, after which the coil, when freed or disengaged from the supporting pin 31, will drop into the chutes 23 and be directed thereby away from the conveyor to suitable location for 10 further treatment or handling as may be desirable.

It will be observed from the foregoing description that the present invention provides a novel construction and arrangement whereby 15 spring coils such, for example, as may be used in bed springs, mattresses, cushions, or the like, may be fed to the conveyor and picked up automatically thereby in spaced relation with respect to each other and conveyed through a tempering 20 oven in such position and relation to each other as will permit the substantially uniform treatment of the spring coils, and after such treatment, the coils are automatically disconnected from the conveyor and directed laterally therefrom for distribution or other handling as may be desired.

Obviously, the present invention is not limited to the precise construction and arrangement shown and described as the same may be variously modified. Moreover, all the features of the invention need not be used conjointly as the same may be used to advantage in variously different combinations and sub-combinations.

What I claim as new and desire to secure by 35 Letters Patent is:

1. In a device of the class described and in combination, a conveyor, substantially flat guide bars adjacent the respective sides of said conveyor and extending substantially parallel thereto, and a plurality of supporting pins on said conveyor extending laterally therefrom and transversely to and beyond the plane of said guide bars.

2. In a device of the class described and in combination, a flexible conveyor, a plurality of pairs of spaced substantially flat guide bars adjacent the respective sides of a run of said conveyor and extending substantially parallel thereto, and a plurality of article pick-up and supporting pins on said conveyor extending laterally therefrom at opposite sides thereof and transversely to the plane of said bars, said pins extending between and beyond the respective pairs of guide bars.

3. In a device of the class described and in combination, a flexible conveyor, a pair of guide bars at one side of said conveyor and extending substantially parallel thereto, an article feeding chute and an article discharge chute adjacent said bars and a plurality of article supporting pins on said conveyor extending laterally therefrom and into the end portions of said chutes for removing articles from said feeding chute and depositing the articles in said discharge chute, and for supporting the articles against said bars during the passage of the articles from one to the other of said chutes.

4. In a device of the class described and in combination, a flexible conveyor, a pair of spaced 70 guide bars at one side of said conveyor and extending substantially parallel thereto, an article feeding chute and an article discharge chute adjacent said bars at the opposite side thereof from said conveyor, and a plurality of spaced ar- 75

5 ticle pick-up and supporting pins on said conveyor extending laterally therefrom between said bars and into the end portions of said chutes for removing articles from said feeding chute and 5 depositing the articles in said discharge chute and for supporting the articles against said bars during the passage of the articles from one to the other of said chutes.

10 5. In a device of the class described and in combination, a flexible conveyor, a pair of spaced guide bars adjacent and on opposite sides of said conveyor and extending substantially parallel thereto, article feeding chutes and article discharge chutes adjacent said bars at the opposite 15 sides thereof from said conveyor, and a plurality of spaced article pick-up and supporting pins on said conveyor extending laterally therefrom at opposite sides thereof between the bars of the respective pairs and into the end portions of said 20 chutes for removing articles from said feeding chutes and depositing the articles in said discharge chutes, and for supporting articles against said bars at the opposite sides of the conveyor during the passage of the articles from the feeding 25 chutes to the discharge chutes.

30 6. In a device of the class described and in combination, a flexible conveyor, a pair of spaced guide bars arranged on each side of said conveyor and extending substantially parallel thereto, a pair of oppositely disposed feeding chutes at the respective outer sides of said pairs of bars and having inwardly sloping portions for directing articles against the respective pairs of bars, and a plurality of article pick-up and supporting pins 35 on opposite sides of said conveyor and extending laterally therefrom between the bars on the respective sides of the conveyor, and adapted to pass through the adjacent ends of the feeding chutes in a manner to engage articles therein 40 positioned against the respective guide bars for removing the articles from the feeding chutes.

45 7. In a device of the class described and in combination, a flexible conveyor, a pair of spaced guide bars arranged on each side of said conveyor and extending substantially parallel thereto, a pair of oppositely disposed feeding chutes at the respective outer sides of said pairs of bars and having inwardly sloping trough-like portions for directing articles against the respective pairs of bars, and a plurality of spaced article pick-up and supporting pins extending laterally and alternately from opposite sides of said conveyor between the bars on the respective sides of the conveyor, and adapted to pass through the adjacent ends of the feeding chutes in a manner to engage articles therein positioned against the respective guide bars for removing the articles 50 separately from the feeding chutes.

55 8. In a device of the class described and in combination, a flexible conveyor, a pair of spaced guide bars arranged on each side of said conveyor and extending substantially parallel thereto in a manner to form slots at opposite sides of the conveyor also extending substantially parallel thereto, a plurality of spaced article supporting pins extending laterally and alternately from opposite sides of said conveyor through said slots for supporting articles thereon and against the outer sides of said bars, a pair of oppositely disposed discharge chutes at the respective outer sides of said pairs of bars and having open portions for the passage of said pins through the adjacent ends of the discharge chutes, said discharge chutes having plates adjacent said bars for retarding the movement of the articles, and out- 60

wardly sloping chute members adjacent said plates for directing the articles away from said conveyor.

65 9. In a device of the class described and in combination, a flexible conveyor, a pair of spaced guide bars arranged on each side of said conveyor and extending substantially parallel thereto in a manner to form slots at opposite sides of the conveyor also extending substantially parallel thereto, a plurality of spaced article supporting pins extending laterally and alternately from opposite sides of said conveyor through said slots for supporting articles thereon against the outer sides of said bars, a pair of oppositely disposed discharge chutes at the respective outer sides of said pairs of bars and having open portions for the passage of said pins through the adjacent ends of the discharge chutes, said discharge chutes having plates at opposite sides of said open portions adjacent said bars and co- 70 operable therewith to form a pair of notches for receiving a portion of the article and retarding the movement thereof, and oppositely inclined members adjacent said plates forming outwardly sloping trough-like chutes for directing the articles away from said conveyor.

75 10. In a device of the class described and in combination, a flexible conveyor, a pair of spaced substantially parallel guide bars arranged on each side of said conveyor in a manner to form slots extending substantially parallel thereto, a pair of oppositely disposed feeding chutes at the respective outer sides of said pairs of bars and having inwardly sloping trough-like portions for directing articles against the respective pairs of bars, a plurality of spaced article supporting pins extending laterally from opposite sides of said conveyor and adapted to pass through the adjacent ends of the feeding chutes in a manner to engage articles therein positioned against the respective guide bars for removing articles from the feeding chutes, said pins being adapted also to pass through said slots for supporting articles on the conveyor and against the outer sides of said guide bars, a pair of oppositely disposed discharge chutes at the respective outer sides of said pairs of bars and having open portions adjacent said slots for the passage of said supporting pins through the adjacent ends of the discharge chutes, said discharge chutes having oppositely inclined stop plates at opposite sides of said slots adjacent said bars and cooperable therewith to form a pair of notches adjacent the respective pairs of bars for receiving a portion of the articles and retarding the movement thereof, and oppositely inclined members adjacent said plates forming outwardly sloping trough-like chutes for directing the articles away from said conveyor after being removed therefrom by said stop plates.

80 11. In a device of the class described, the combination with a spring coil tempering oven having inlet and outlet openings, of a continuous flexible conveyor extending through said oven between the inlet and outlet openings thereof for conveying coils therethrough, a pair of laterally spaced substantially parallel guide bars extending through said oven on each side of said conveyor in a manner to form elongated slots extending substantially parallel thereto, a pair of oppositely disposed feeding chutes outside said oven adjacent the inlet opening thereof, said chutes being positioned at the respective outer sides of said pairs of bars and having inwardly sloping trough-like portions for directing the end 85 90 95

portions of spring coils against the respective pairs of bars, a plurality of spaced coil supporting pins mounted on and extending laterally from opposite sides of said conveyor and adapted to pass through the adjacent ends of the feeding chutes in a manner to engage the end portion of spring coils positioned therein against the respective guide bars for removing the coils from said chutes, said pins being also adapted to extend through and to be moved along said slots for supporting the springs on opposite sides of the conveyor and against the outer sides of said guide bars, and a pair of oppositely disposed discharge chutes outside said oven adjacent the outlet opening thereof, said discharge chutes having means associated therewith for removing the coils from said pins and having outwardly sloping portions for directing the coils away from said conveyor.

12. In a device of the class described and in combination, a conveyor, guide bars arranged adjacent the side of said conveyor and extending substantially parallel thereto, a feeding chute at the side of said conveyor adjacent the outer side of said bars and having inwardly sloping portions for directing spring coils against said bars at an angle thereto, and a plurality of pick-up and supporting members mounted on the side of said conveyor and extending therefrom past the outer side of said bars adjacent said feeding chute and adapted to pass through an adjacent portion of the chute in a manner to engage an outer convolution of a spring coil in said chute positioned against the guide bars for removing the spring from said chute. 5 10 15

FRANK N. SCHINDLER.
